UNITED STATES PATENT OFFICE.

AUGUST W. L. HARTBAUER, OF DETROIT, MICHIGAN.

FOLDABLE SEAT.

1,218,857.

Specification of Letters Patent. Patented Mar. 13, 1917.

Application filed March 6, 1916. Serial No. 82,304.

To all whom it may concern:

Be it known that I, AUGUST W. L. HARTBAUER, a citizen of the United States, residing at Detroit, in the county of Wayne and 5 State of Michigan, have invented a new and useful Foldable Seat, of which the following is a specification.

This invention relates to foldable seats especially adapted for use auxiliary to the 10 seats of motor vehicles, and it consists in the novel construction and arrangement of parts as hereinafter set forth and claimed.

The invention has for its object the provision of a light, strong portable seat of 15 simple and inexpensive construction, which may be mounted in the tonneau space of motor-vehicles to serve as an auxiliary seat for use in emergencies when desirous of increasing the seating capacity of the vehicle, 20 and wherein provision is made for spring cushioning the seat upon a hinged interlocking supporting standard adapted to be detachably mounted in a floor socket, and which may be compactly folded together 25 with the body of the seat to facilitate storing when not in use.

A preferred form of embodiment of the essential features of the present invention is illustrated in the accompanying drawings, 30 in which,

Figure 1 is a side elevation of the seat in the unfolded or normal position.

Fig. 2 is a rear elevation of the seat in the position shown in Fig. 1.

Fig. 3 is a central vertical section on dotted line 3—3 of Fig. 2.

Fig. 4 is a cross section on dotted line 4—4 of Fig. 2.

Referring to the parts of the device by 40 the characters of reference marked on the several views of the drawings, 1 represents a curved tapering upright back member preferably cast of malleable iron, the body of which is of the form of an open triangular frame provided with a surrounding laterally projecting stiffening rib 2 and having a cross portion 3 connecting the sides of the frame midway the ends thereof. The upper end of the back member 1 is formed 45 with a T-shaped plate 4 to which an arcuate back rest 5 is attached by screws, as at 6.

The lower end or base of this back member is inwardly turned or offset to form an inclined bearing shoulder 7, and projecting laterally from the inner face upon opposite 55 sides of said member are lugs or ears 8, to which the upturned ends of a pair of angular arms 9 are pivotally connected, respectively, by studs as at 10. These arms, which are secured by screws 11 to the under face 60 of a circular seat 12, engage at the juncture of their angular portions with the shoulder 7 and serve to normally support said seat in the proper angularly extended relation upon said back member. 65

Formed integral with the base of the back member, and depending centrally therefrom, is a bifurcated extension forming a pair of spaced parallel tongues 13 having formed transversely therethrough vertically elongated apertures 14. The upper portions of 70 said apertures are slightly inclined rearwardly and terminate in outwardly leading right-angled channels 15 which are formed in registering alignment in the inner faces 75 of enlarged portions 16 of said tongues at their juncture with the base of said back member, as clearly shown in Figs. 2 and 3.

A yoke-shaped bracket 17, upon which the back-member is pivotally mounted to swing 80 and to interlock therewith, is formed with parallel lateral extensions 18 at opposite ends upon one side and has upon the opposite side, near the upper end thereof, a vertically and laterally extending ear 19 which 85 lies freely within the space between the tongues 13, and extending laterally from opposite sides of said ear are axially aligned trunnions 20 which are freely received, respectively, in the elongated apertures 14 of 90 said tongues. Said trunnions are entered in said apertures by first positioning the bracket at the rear of the back member so as to enter the ear 19 between the tongues 13 and pass said trunnions through the channels 95 15 into said apertures. The bracket is then moved downwardly to carry the trunnions into the lower ends of the apertures at which points said apertures are enlarged rearwardly by arcuate depressions 21 to permit 100 lateral movement of said trunnions and afford clearance between the back face of the

bracket and the rear end portions of the tongues to enable the bracket to be swung about the ends of said tongues into a vertical portion upon the opposite edges thereof, 5 as shown in Figs. 1 and 4. In this position the back face of the bracket, which is oppositely inclined as at 22 (see Fig. 4) will be brought into parallel engagement with the correspondingly inclined edges 23 of said 10 tongues and through the wedging engagement of the trunnions with the inclined edges of the elongated apertures by the gravity of the back member, said bracket and back member will be firmly locked 15 against relative lateral and swinging movements.

To provide cushioning means for supporting the seat, I employ an upright or standard 24, preferably tubular, which extends 20 freely at its upper end through the extensions 18 of the bracket 17, and embracing said standard and interposed between said extensions is an expansive coiled spring 25 which abuts at one end against the upper extension and rests at its opposite end upon a pin 26 which extends transversely through said standard and engages the lower extension of said bracket, said pin serving as a stop to prevent the withdrawal of the standard and 30 to limit the upward travel of the bracket in its movement thereon under the tension of said spring. The lower end of the standard may be supported vertically in a flanged socket 27 adapted to be secured to the floor 35 or other suitable base to form a support upon which the seat may revolve and from which the standard may be withdrawn when desirous of removing the seat.

When removing the standard from the 40 socket by lifting upwardly on the back member of the seat the tongues on said member will be withdrawn from engagement with the back face of the bracket and the trunnions of said bracket will pass from wedging engagement with the inclined edges of the apertures of said tongues into the enlarged lower extremities of said apertures, in which position the bracket may then be swung together with the standard upon the 45 rear of the back member, when it may be frictionally held in position by forcing upwardly thereon to cause the trunnions to engage the opposite edges of the apertures with the bracket bearing against the lower 50 rear ends of the tongues and with the end of the standard contacting with the cross portion 3 of the back member in an angular folded position therewith, as indicated by dotted lines in Fig. 3. The seat portion may 55 also be folded upon the back member as shown by dotted lines, thus enabling the parts to be compactly grouped and reduced in bulk to facilitate storing when not required for use.

I claim:—

1. In a foldable seat, a back member having a seat member hingedly mounted thereon, a supporting standard adapted for detachable engagement with a floor socket, connecting means mounted on said standard 70 and having pivotal and slidably interlocking engagement with said back member to retain said member in fixed extended relation to said standard and to permit said standard to swing thereon into folded relation 75 with said seat and back member.

2. In a foldable seat, a back member having a seat member mounted thereon, a supporting standard, and a spring-pressed bracket mounted on said standard and pivotally and slidably connected with said back member to fold thereon and to interlock in 80 an extended relation therewith.

3. In a foldable seat, a back member carrying a seat member and having a bifurcated 85 extension provided with elongated apertures therein, a supporting standard, and a bracket mounted on said standard and having trunnions engaging in the apertures of said bifurcated extension to retain said 90 bracket in fixed parallel engagement with said extension and to permit said bracket to swing about the end thereof.

4. In a foldable seat, a back member having a seat member hingedly mounted to fold 95 thereon, a supporting standard, and a bracket mounted on said standard and pivotally connected to interlock with said back member and to swing thereon into folded relation with said seat and back member.

5. In a foldable seat, a back member carrying a back rest at its upper end and terminating at its lower end in a bifurcated angular extension having elongated apertures formed therethrough, a seat member hingedly mounted on said back member and supported on said angular extension, a supporting standard, and a bracket mounted on said standard, said bracket having an ear provided with trunnions engaged in the 105 apertures of said extension to hingedly connect and slidably interlock said bracket with said back member.

6. In a foldable seat, a back member carrying a seat member and having a forked extension thereon, a supporting standard, a coiled spring embracing said standard, a bracket mounted on said standard and supported on said spring, and means on said bracket coöperating with said forked extension for hingedly connecting and slidably interlock said bracket with said back member.

7. In a foldable seat, a back member carrying a seat member and having a forked 115 extension provided with inclined elongated apertures therein, said apertures terminating at their upper ends in outwardly leading

recesses in the opposed faces of said forked extension, a supporting standard, and a spring-pressed bracket mounted on said standard and having an ear provided with 5 trunnions, said trunnions adapted to be entered in said apertures through said recesses

and to engage the inclined portions of said apertures to retain said bracket in wedging engagement with said forked extension.

In testimony whereof, I sign this specification.

AUGUST W. L. HARTBAUER.
